UNITED STATES PATENT AND TRADEMARK OFFICE
Certificate

Patent No. D586,959 S

Patented: February 17, 2009

On petition requesting issuance of a certificate for correction of inventorship pursuant to 35 U.S.C. 256, it has been found that the above identified patent, through error and without any deceptive intent, improperly sets forth the inventorship.

Accordingly, it is hereby certified that the correct inventorship of this patent is: Joseph Geringer, Merrimack, NH (US); Stephen Hickey, Somerville, MA (US); Thomas Swyst, Arlington, MA (US); and Duane L. Gilbert, Jr., Goffstown, NH (US).

Signed and Sealed this Seventh Day of May 2013.
